CARPORT

Einar Svensson, 2248 NW. 190th Place,
Seattle, Wash. 98177

Continuation-in-part of design application Ser. No. 12,557,
July 1, 1968. This application June 25, 1969, Ser. No.
17,874

Term of patent 14 years

Int. Cl. D25—04

U.S. Cl. D13—1

FIG. 1 is an end elevational view of an end of the carport and shows the end wall, and said carport having two end walls the same as the one shown;

FIG. 2 is a front elevational view of the carport and illustrates the two end walls, and the back elevational view of the carport is the same as the front elevational view of the carport; and,

FIG. 3 is a perspective view at an angle illustrating the drive through feature of the carport.

This application is a continuation-in-part of my United States design patent application Ser. No. 12,557, entitled Carport, filed July 1, 1968 and now abandoned.

I claim:

The ornamental design of a carport, substantially as shown and described.
